FIG. 4.

FIG. 3.

FIG. 2.

FIG. 5.

UNITED STATES PATENT OFFICE

JOHN L. McMILLAN, OF SYRACUSE, NEW YORK, ASSIGNOR TO McMILLAN BOOK COMPANY, OF SYRACUSE, NEW YORK, A CORPORATION OF NEW YORK

TRANSFERRING DEVICE

Application filed April 23, 1928. Serial No. 272,139.

This invention relates to a new and improved transferring device for use with loose leaf binders of the type usually designated as ring binders, and is particularly designed for use with such binders when the same are to be used as a visible index.

When loose leaf binders are used as a visible index the sheets used with the binders are less in height than the binder itself so that they may be inserted in the binder with a portion of their faces exposed.

When a sheet is removed from a binder because the account or record kept on the same has been closed it is usually desirable to place a new sheet in the binder at the bottom thereof. When this is done it is necessary to move upwardly the sheets which were positioned next below the sheet which was removed. In order to accomplish this operation quickly and easily it is desirable to have some means which will direct the movement of a sheet laterally in the binder and yet which will at the same time function as a retaining means for the sheet. This is particularly desirable when a plurality of sheets are to be moved for it obviates the necessity of taking them from one set of prongs and placing them on another set of prongs with the liability of the sheets becoming disarranged so that holes provided in them will not be in registration.

The main object of my invention is to provide a device which may be used with a loose leaf binder as desired and which will direct and facilitate the transfer of sheets from one set of prongs of the binder to another set of prongs and during the operation cause the sheets to move laterally in the book.

Another object of my invention is to provide a means of the character described which can be used interchangeably with a plurality of loose leaf binders.

Other objects and advantages relate to the size and shape of my device and the means provided for its easy and convenient use with different types of loose leaf binders all as will more fully appear from the following description taken in connection with the accompanying drawings in which:

Figure 1 is a top plan view of a binder with the prongs in the open position and with my

device assembled in the binder, the covers of the binder being partially broken away.

Figure 2 is an end view of a binder which I have shown as a binder with which my device may be utilized, the prongs of the binder being in the closed position.

Figure 3 is a view similar to Figure 2 with the prongs of the binder in the open position.

Figure 4 is a section on line 4—4 of Figure 1.

Figure 5 is a perspective view of my device.

It will be understood that my device may be utilized with loose leaf binders of different designs but for the purpose of illustrating the design and functioning of my structure I have here shown a binder of a specific type composed of back members —1— and —2— hingedly connected on their inner longitudinal edges by hinges —3— and —4—. Back member —1— carries a back plate —5— extending vertically above its outer longitudinal edge. A top plate —6— approximately right angular in cross section is positioned on the upper face of back member —1— in spaced relation to back plate —5— and is provided with an outwardly extending upper face —7— registering with the upper edge of back plate —5—. A cover plate —8— is positioned on the upper and inner face of back member —1— and overlies top plate —6— to lock the same in position.

Similarly back member —2— is provided with a back plate —9— and top plate —10— having an upper portion —11— in registration with the upper edge of back plate —9— and a cover plate —12— all assembled in the same way as has just been described with relation to the similar members on back member —1—.

The upper faces —7— and —11— of back plates —5— and —9— are each provided with a plurality of holes 13—13 in longitudinal spaced relation. Prongs 14—14 are secured by welding or other convenient means in spaced relation in holes 13—13 in upper face —7—. Prongs 14'—14' are also secured in holes 13—13 in upper face 11 but are grouped in sets as shown on Figure 1 and in this case the end sets consist of two prongs each and the intermediate sets consist of three prongs

each although it is obvious that the combinations may be varied as desired. The position of prongs 14-14 in upper face 7 in relation to the position of the sets of prongs 14-14 in upper face 11 is such that when the binder is in the closed position, as shown in Figure 2, the prongs 14-14 in upper face 7 will register with holes 13-13 in upper face 11 and similarly the prongs 14-14 in upper face 11 will register with holes 13-13 in upper face 7.

For the purpose of releasably holding the binder in the closed position or in the open position as desired I provide at both ends of back members 1 and 2 a locking device and inasmuch as the locking devices at the opposite ends of back members 1 and 2 are similar in construction a description of one will be a description of both.

My locking device may best be understood by referring to Figures 2 and 3. A plate 15- approximately square in shape is affixed to the end of back member 1 by any convenient means not shown and is provided with an outwardly extending lug 16.

A second plate 17- is affixed to the end of back member 2, plates 15- and 30-17- being disposed in approximately the same plane. Plate 17- is provided with a slot 18- for a purpose hereinafter to be described. A locking plate 19- is pivotally mounted in back member 2- by means of a rod 20- which extends longitudinally through back member 2- and which is rotatably mounted therein. Locking plate 19- carries at one side of its pivot an elongated slot 21- coacting with lug 16-. On the other side of the pivot locking plate 19- carries an outwardly extending tab 22- and a tongue 23- extending inwardly through slot 18-. A spiral spring 24- is positioned on rod 20- abutting against the inner face of plate 17- and having one end in engagement with the under surface of tongue 23- to normally exert upward pressure on tongue 23-. Elongated slot 21- has a recess 25- at one end thereof and has at the other end a recess 26-. When the binder is in the closed position as shown in Figure 2 the lug 16- will be positioned in recess 26- and may only be released therefrom by moving locking plate 19- about its pivot by downward pressure on tab 22- against the tension of spring 24-. When the binder is in the open position as shown in Figure 3 lug 16- will be in recess 25- and can only be released therefrom by similar pivoting of locking plate 19- by the downward movement of tab 22-. Locking plate 19- is rigidly secured to the end of rod 20- and the similar locking plate 19- which is positioned at the oppo-

site end of the binder is also rigidly secured to an end of rod 20- so that downward pressure on either of tabs 22- will cause a pivotal movement of both the locking plates 19-.

As perhaps may best be seen from Figure 5 my transferring device 27- consists of a short rod preferably circular in cross section and having both ends of the shape of a truncated cone as shown at 28- with a recess as 29- in each end. Recess 29- is of a size and shape to receive the pointed ends 30- of prong 14- and 14'.

As perhaps may best be seen from Figure 1 the length of my transferring member 27- is such that when one end is placed on a prong 14- the transferring member 27- will extend obliquely across the binder so that its other end will register with the point 30- of a longitudinally offset prong 14' of an opposite set. The prongs 14-14 in upper face 7- being in staggered relation to the sets of prongs 14'-14' in upper face 11-, my transferring device 27- may be positioned diagonally of the binder towards the right or left as desired, one position being shown in solid lines on Figure 1 and the other position being shown in dotted lines on Figure 1 at -a-.

It will be understood that the length of transferring member 27- is such that in order to place it in position between two prongs 14-14' they must be sprung slightly apart so that when transferring member 27- is in position it will be held therein by the resiliency of prongs 14-14'.

In utilizing my transferring member 27- the sheet or sheets 31-, having a plurality of holes 32- in spaced relation along one longitudinal edge thereof, are placed on one set of prongs 14- and the binder is then opened to the position shown in Figure 3. I then place in position my transferring member 27- with one end in position on prong 14- extending upwardly through sheet 31- and with its other end in position on an opposing prong 14'-. It is preferable when a transfer of sheets is to be made to use a second transferring member 27- coacting with a second prong 14- extending upwardly through sheet 31- so that the sheet 31- will be held in aligned relation to prongs 14'- as the sheet is moved off from the prongs 14-14, on which it was initially positioned, onto the opposite set of prongs 14'-14'.

In Figure 1 I have shown in position one transferring device 27-, in solid lines, and a second device in position, in cross section, I have also shown, in solid lines, a sheet 31- and it will be seen that when sheet 31- is raised upwardly from prongs 14-14 onto transferring devices 27-27- the sheet 31- will be moved obliquely of the binder into a position to move off from

transferring devices 27—27 onto the opposite set of prongs 14'—14'. Having been guided in an oblique direction by transferring device 27—27, sheet 31— will have been moved laterally of the binder into the position shown in dotted lines on Figure 1.

The transfer of the sheet 31— having been completed the transferring devices 27—27 are removed from prongs 14—14' and the binder may then be closed.

It will be understood that the length of my transferring device 27— and that the number and position of prongs 14—14' may be varied so that the distance of the lateral movement of sheets 31— in the binder may be varied at will. For example, in the transferring operation just described I have shown a transferring device 27 of such a length that the sheet 31— will be transferred from a prong 14 on upper face 7 to a prong 14' on upper face 11 a distance corresponding to two holes 32 in sheet 31. It is obviously possible, however, and frequently desirable to use a transferring device of such a length that the sheet 31 will be transferred a distance corresponding to one hole 32 in sheet 31. A transferring device of a proper length to accomplish this last mentioned transfer is indicated in position by dotted lines b—b on Figure 1, the transfer being accomplished in the same manner as hitherto described.

It will also be understood that the particular shape of the two ends of my transferring device 27— may be changed so that it will be able to coact with different types of prongs. It will also be understood that my transferring device 27— may be curved or S-shaped instead of straight as herein shown, for although I have shown and described a specific structure and form of part as an exemplification of an embodiment of my invention I do not desire to restrict myself to the exact shape, size or relation of parts as various changes may be made within the scope of the appended claims.

What I claim is:

1. In a device of the class described, a pair of opposed back members, a prong carrying member affixed to each back member, a plurality of prongs affixed in each prong carrying member in longitudinally and correspondingly spaced relation, and adapted to receive a sheet having a plurality of holes in spaced relation along one edge thereof, and a guiding member having one end removably positioned on the end of a prong of one set and the other end removably positioned on the end of a longitudinally offset prong of the opposite set for guiding a sheet from the first named prong to the second named prong.

2. In a device of the class described, a pair of opposed back members, a prong carrying member affixed to each back member, a plurality of prongs affixed in each prong carrying member in longitudinally and corre-

spondingly spaced relation, and adapted to receive a sheet having a plurality of holes in spaced relation along one edge thereof, and a guiding member having one end removably positioned on the end of a prong of one set and the other end removably positioned on the end of a prong of the opposite set for guiding a sheet obliquely of the back members from the first named prong to the second named prong.

3. In a device of the class described, opposed sets of prongs in correspondingly spaced but staggered relation, and adapted to receive a sheet having a plurality of holes along one edge thereof, and a connecting member having one end removably positioned on the end of a prong of one set and having the other end removably positioned on a longitudinally offset prong of the opposite set for guiding a sheet from one set of prongs onto the other set of prongs.

4. In a loose leaf binder, sets of opposed prongs in correspondingly spaced but staggered relation one to the other, and adapted to receive a sheet having a plurality of holes along one edge thereof, a guiding member having one end removably positioned on the end of a prong of one set and having the other end removably positioned on the end of a prong of the opposite set whereby a sheet may be guided obliquely of the binder from one set of prongs to the other set of prongs.

5. As an article of manufacture, a connecting member for longitudinally offset prongs of a loose leaf binder comprising a rod having in each end thereof a recess adapted to receive and retain the end of a prong substantially as shown and described.

6. As an article of manufacture, a connecting member for longitudinally offset prongs of a loose leaf binder comprising a rod having in each end thereof a recess adapted to receive and retain the end of the prong, said rod being slightly longer than the distance between the ends of the prongs to be connected, whereby it will be held in position by the inherent resiliency of the prongs.

In witness whereof I have hereunto set my hand this 9th day of April, 1928.

JOHN L. McMILLAN.
